E. HYMAN

STAIR COVERING

Filed June 9, 1923

Inventor
Elias Hyman

By *Solomon Polackoff*
Attorney

UNITED STATES PATENT OFFICE.

ELIAS HYMAN, OF BROOKLYN, NEW YORK.

STAIR COVERING.

Application filed June 9, 1923. Serial No. 644,319.

To all whom it may concern:

Be it known that I, ELIAS HYMAN, a citizen of the United States, residing at Brooklyn, in the county of Kings and State of New York, have invented certain new and useful Improvements in Stair Coverings, of which the following is a specification.

This invention relates generally to stair covering means, having more particular reference to a novel form of covering comprising a number of pads which are applied individually to the separate steps, the invention having for an object the provision of a pad of this sort which takes the place of a continuous length of carpet and which can be readily applied to the stair or removed therefrom.

For further comprehension of the invention, and of the objects and advantages thereof, reference will be had to the following description and accompanying drawings, and to the appended claims in which the various novel features of the invention are more particularly set forth.

Fig. 1 of the drawings is a plan view of my improved stair pad.

Fig. 2 is a side view thereof.

Fig. 3 is an enlarged fragmentary transverse sectional view indicating the manner of fastening the fabric to the base element.

Fig. 4 is a like view but showing a modified arrangement.

Fig. 5 is a fragmentary transverse sectional view showing more particularly the means for detachably securing the pad in place.

Fig. 6 is a detail perspective view showing the stud member of the pad securing means. Fig. 7 is a detail sectional perspective view showing the socket member of the pad securing means.

In constructing my improved stair pad I provide a sheet or plate of metal 10 which is bent along one side to form a depending flange which overlies the front of the step 11, the main body of the member 10 resting on the step. As will be understood this member 10 is of a size to substantially cover the step, although the ends of the latter may be left exposed as is usual with stair carpets. To the frame comprised by this plate 10 with its depending flange 10' is attached the pad proper which comprises top and bottom elements 14 and 15 respectively between which is a filler 16, these top and bottom ele-

ments being secured together along their edges, and also to the plate 10.

In the form of the invention shown in Fig. 3 the top element 14 of the pad is comprised of a strip of carpet material, while the bottom element may be made of canvas, drill or other suitable material such as cardboard. The filling 16 may be of silk floss or other suitable material. The two members 14, 15 are stitched together along their edges as indicated at 17 in Fig. 3 and are gripped by flange elements extending around the plate. In securing the members to the plate the extreme marginal portion of the latter, indicated at 18 in Fig. 3, is first bent over the stitched edges and then the edge parts are again bent over on the body of the plate to the position shown in Fig. 3, thus securely locking the edges of the fabric to the plate, this construction providing the 75 channelled flanges 19 which are bent over the body of the plate and have the edges of the members 14 and 15 gripped in their channels. In the construction shown in Fig. 4 the edges of the members are folded over on 80 a wire 20 and then stitched together, after which the edges of the plate 10 are folded over as above set forth.

The pad may be attached in place by screws for which suitable openings are provided in the corners thereof, or I may utilize a novel fastening means which permits of the ready removal and application of the pad. As here shown a pair of studs 25 are fixed to the depending element and are 90 adapted to engage in suitable sockets in the front of the step 11. Fixed in the rear part of the step are a pair of socket members 26 which are adapted to be engaged by rotary studs 27 carried by the plate 10. these studs 95 carrying pins such as 28 which project from the sides thereof and engage in bayonet grooves such as 29 in the inner walls of the sockets. In the top of each stud 27 is a transverse slot 30 which is extended downward along the sides of the stud as at 31. In these extensions 31 are fixed flat springs 32 which are attached at their upper ends to the bottom wall of the U-groove thus formed and which carry triangular latch members 33 which are urged by the springs into recesses 34 formed in the sides of the sockets 26.

When the pad is secured in position on the step the pins 28 on the studs 27 are 110

engaged in the horizontal lower portions of the bayonet grooves 29, being held in this position by the engagement of the latches 33 in the recesses 34. The pad is thus locked 5 in place. When it is desired to remove the pad from the stair a suitable forked tool is inserted in the slot 30 and the legs thereof engage over the latches and move them into the grooves 31, the stud 27 being then turned 10 by means of the tool until the pins 28 thereon register with the vertical legs of the bayonet slots 29. After both studs have been thus turned the rear edge of the pad may be swung up to clear the studs from 15 the sockets 26 and the pad is then slipped forward to free the studs 25 at the front thereof. In applying the pad the above described series of operations is reversed. It will be understood that the studs 25 and 27 20 may have a sufficiently loose fit in their sockets to allow of the slight vertical swinging movement of the covering to insert or remove the studs 27 when the studs 25 are engaged in their sockets.

25 As will be apparent I have provided a simple and readily applicable form of stair covering means which can be constructed at small expense, and can be quickly and easily removed when desired.

30 Having thus described my invention what I claim as new and desire to protect by Letters Patent of the United States is as follows:

35 1. A stair pad comprising a metal plate, a pad proper seated thereon and comprising top and bottom elements and a filling therebetween, said top and bottom elements being stitched together along their edges and having the stitched edges folded back

upon the said elements, and the edges of 40 said metal plate being doubled over the said backwardly folded stitched edges.

2. A stair pad comprising a metal base element, and a fabric superstructure carried thereby, and means for removably securing 45 said base element to a stair, said means comprising a socket element adapted to be fixed in the step and formed with a bayonet groove, a stud rotatable in the said base element and carrying a pin adapted to engage in the said groove.

3. A stair pad comprising a metal base element, and a fabric superstructure carried thereby, and means for removably securing 50 said base element to a stair, said means comprising a socket element adapted to be fixed in the step and formed with a bayonet groove, a stud rotatable in the said base element and carrying a pin adapted to engage in the said groove, and latch elements 55 carried by the stud and engaging in recesses in the socket to hold the stud against rotation.

4. A stair pad comprising a metal plate, a pad proper seated thereon and comprising 60 top and bottom elements and a filling therebetween, said top and bottom elements having their edges doubled back to leave a pocket extending around the edge of the pad proper, a metal ring inserted in said pocket, 65 and a flange member on said metal plate doubled back over said pocket and bearing on the said doubled back edges within the confines of the said ring.

70 In testimony whereof I have affixed my 75 signature.

ELIAS HYMAN.
